H. HIGGIN.
METAL FENCE POST.
APPLICATION FILED NOV. 6, 1912.

1,056,173.

Patented Mar. 18, 1913.

UNITED STATES PATENT OFFICE.

HENRY HIGGIN, OF NEWPORT, KENTUCKY.

METAL FENCE-POST.

1,056,173.

Specification of Letters Patent. **Patented Mar. 18, 1913.**

Application filed November 6, 1912. Serial No. 729,741.

To all whom it may concern:

Be it known that I, HENRY HIGGIN, a citizen of the United States, and a resident of the city of Newport, in the county of Campbell and State of Kentucky, have invented certain new and useful Improvements in Metal Fence-Posts, of which the following is a full, clear, and exact description, reference being had to the accompanying drawings, forming part of this specification.

My invention relates to fence posts formed from an integral piece of sheet metal, usually of galvanized iron, and provided with means for securing fence wires thereto.

15 The object of my invention is to provide a construction in which the metallic structure shall not be weakened by the formation of tongues in the body of the metal, while at the same time tongues shall be provided 20 forming an integral part of the construction, so that separate devices for supporting and holding the wires shall not be necessary.

In the drawings, Figure 1 is a perspective view of one of my improved posts showing 25 the wires in place. Fig. 2 is a central longitudinal section of a portion of the post. Fig. 3 is a cross section of the same. Fig. 4 is a plan view of a portion of the sheet from which the post is constructed.

30 The posts are formed from a single plate of sheet metal 1, which is bent into tubular form, with the side edges 2, 3, abutting. The sheet is so cut that when bent into shape, the tubular posts shall be tapering from top 35 to bottom, with a uniform taper and broader at the bottom. Along each side edge of the flat sheet 1 before it is bent into shape, a series of tongues 4, 4, are cut, and as many sets of tongues as it is desired to secure wires 40 to the posts are provided, with the two tongues of each set directly opposite each other on the blank, and with each set of tongues cut in from the top, so that each tongue will be integrally connected with the

body of the blank at the bottom, at 5. When 45 the tongues are cut, they are bent backward slightly so as to project from the plane of the sheet, and when the sheet is bent into cylindrical form, as the tongues are cut from the side edges, as shown, and project 50 upwardly, they form hooks to receive the wires 6.

Where the quality of the ground will permit, the posts are driven in by striking them on top, or they may be placed in post holes 55 and securely tamped. The wires 6 are then located in place and the tongues preferably bent around the wire, as shown at 7 in Fig. 2. Inasmuch as the holding tongues are in pairs, when clamped around the wire 6 they 60 not only hold the wires securely in place, but also lock and hold the cylindrically shaped metal from springing open at the seam, thus serving two purposes. In addition to this, inasmuch as the tongues are cut from the 65 side edges of the metal instead of the body of the metal, the strength of the sheet metal is not weakened, and a much more rigid and substantial post is the result over sheet metal posts of the same thickness of metal 70 in which the holding tongues are struck up from the body of the metal.

Having thus described my invention, what I claim as new and desire to secure by Letters Patent, is:—

75 A metallic fence post formed from an integral blank of sheet metal, with tongues cut from the side edges of the metal, said tongues formed in pairs, one in each side edge, adapted to meet at the seam when the 80 blank is bent to shape, said tongues projecting upwardly to form hooks to support the fence wire and to lock the side edges of the blank to prevent opening of the seam.

HENRY HIGGIN.
